UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD OF RANDING SHOES AND TRIMMING THE HEELS THEREOF.

Application filed September 20, 1924. Serial No. 738,848.

This invention relates to shaping the peripheral contours of shoes in process of manufacture. The invention is hereinafter described with special reference to randing 5 shoes having spring heels and to trimming or shaping the heels of such shoes, but in various aspects it is not necessarily restricted to the shaping of spring heeled shoes.

The shaping of spring heels has heretofore been a slow, troublesome and relatively costly operation—costly because it has required the highest degree of skill, slow because the operative has been dependent upon his eye, judgment and skill in manipulating the work and troublesome because of a number of conditions that need not all be herein set forth but which are well-known to those experienced in the art. It will be well, however, to point out some of the 20 causes of difficulty in such work.

In the manufacture of a spring-heeled shoe the wedge element or base of the heel is usually died out approximately to a final shape and size, and is attached to the shoe 25 manually and located by eye as nearly as possible in register with the heel-seat or counter, without regard to the sole, while the sole, which is located with more regard to register of the forepart than to 30 register of the heel-end, always projects beyond the wedge element at the sides and back. Furthermore, the operative whose duty it is to shape the heel has no pre-shaped toplift to control the depth of trimming 35 and to assist his manipulation of the shoe as in shaping other types of heels, and so it has become the custom simultaneously to trim and rand a spring heel by slowly trimming off and randing a little here, a little there, inspecting the result, repeating 40 the operation, again inspecting the result, and so on until, in the judgment of the operative, the contour of the heel approximates the shape of the counter. Consequently, the 45 shaping of spring heels, as heretofore practiced, is essentially an edge-trimming operation wherein the operative has been obliged to rely for contour, smoothness of surface and randing upon his eye and 50 skill of manipulation as in trimming the edge of a sole around the forepart. For this work it has been customary to use only fine-cutting toothed cutters of the same type as those used for trimming foreparts. Not

only does the use of such cutters retard production, particularly when used as above stated, but if the heel part of the sole projects very far beyond the wedge element, as do the corners of a block sole, the shaping operation is thereby necessarily rendered still slower as well as more difficult. 55

In some respects spring-heel trimming is attended by more difficult conditions than forepart trimming. For example, a spring heel is thicker than a forepart and therefore requires more effort to maintain it against the cutter, one layer of stock, that is, the heel-end of the sole, projects beyond the other or others, the extent of such projection varies greatly at successive 65 points, and the thickness of a spring heel varies at successive points because the wedge elements are not made of accurately graded stock. Again, shoemaking standards require greater accuracy at the heel-end than 70 elsewhere, since the extension of the shoe bottom at the heel-end must be narrow and uniform while at the shank and forepart it is wider and commonly of varying width through choice. Thus, while accuracy is as 75 much to be desired in forepart trimming as in heel trimming, inaccuracies are more noticeable in the latter because, in comparison to the relatively narrow width of the extension at the heel, they are proportionally greater than inaccuracies of the same 80 magnitude in the forepart.

The spring-heel-trimming operative cannot, as a practical matter, produce a uniform width of extension and uniform randing at 90 the same time under the existing conditions, nor can he produce two shoes alike. Any real attempt to avoid palpable irregularities retards production.

In view of the above-mentioned conditions, an object of the invention is to provide an improved method adapted for use in trimming spring heels by which a heel may be shaped to produce a uniform width of extension beyond the rand-crease and by 95 which uniform rand trimming or "randing" 100 may be insured.

The term "rand" as used herein is not intended to mean the well-known U-shaped piece of leather commonly inserted between 105 the sole and heel, but is intended to mean the marginal surface projecting from the rand crease.

Again, the term "heel" as used herein is intended to include the heel end of a sole irrespective of whether such heel end lies at the tread surface, as in the case of a spring heel, or between the counter portion of the shoe and an attached heel body, and from this it is to be understood that in the one case the rand or marginal extension projecting from the rand-crease is the upper surface of the heel body or wedge element, whereas in the other case it is the marginal portion of the heel end of the sole.

In one aspect, the invention consists in initially trimming the periphery exclusively of a heel to produce a uniform width of extension from the rand-crease by using the rand-crease to control the course of such trimming, and thereafter trimming the rand and the periphery of the heel simultaneously to final shape. Preferably both the randing and the final trimming of the periphery will be controlled by the rand-crease to insure uniformity in the width of the extension.

In another aspect the invention provides for rapid production by employing a coarse cut to take off the greater part of the surplus stock from the periphery of the heel incidentally to reducing the extension to uniform width, and employing a fine cut thereafter to rand the heel and to smooth the entire peripheral surface previously formed with the coarse cut.

Furthermore, in the manufacture of shoes it is desirable to insure uniformity and accuracy in locating the fasteners that are inserted through or into the heel. The term "fasteners" is here used in its broad sense to include nails, pegs and slugs, even though the latter are sometimes so short that they have little, if any, fastening function but chiefly, at least, a wear-resisting and ornamental effect. Many machines now used for inserting fasteners in spring heels comprise a gage arranged to run on the periphery of the heel to locate the fasteners, but, obviously, if the periphery is not true that is, if the width of the extension is not uniform, its variations will produce corresponding variations in the placing of the fasteners.

Accordingly another object of this invention is to provide an improved method adapted for use in the making of shoes by which the periphery of the rand-crease extension or base of a heel may be used to insure accurate and uniform placing of the fasteners. This result is not only desirable for its ornamental effect when the heels are to be slugged or pegged, but, as to fasteners used to anchor the heel to the heel-seat, is essential to avoid striking the lasting tacks previously inserted and still permit placing the fasteners inside the line of the rand-crease.

Therefore, in another aspect the invention

consists in securing a heel to the heel-seat of a shoe, trimming the periphery of the heel to a uniform distance from the rand-crease as by using the latter to determine the course of trimming, and inserting a series of fasteners into the heel, if not also into the heel-seat, at a uniform distance from the rand-crease by using the uniformly trimmed periphery to locate such fasteners. This procedure may be, and preferably is supplemented by a final trimming operation to trim the rand and smooth the periphery of the heel as hereinbefore explained.

The accompanying drawings illustrate a turn shoe and a welt shoe, and apparatus suitable for trimming and randing the heels and locating fasteners in the heels according to the present invention.

In the drawings,

Fig. 1 is a front elevation of the upper portion of an improved heel-shaping machine comprising a coarse cutter for doing the bulk of the shaping of the periphery, and a fine cutter for trimming the rand and smoothing the periphery.

Fig. 2 is a side elevation of the assemblage for performing the first shaping operation, the direction of view being from left to right with reference to Fig. 1.

Fig. 3 is a side elevation of the assemblage for performing the second or final trimming operation, the direction of view being the same as Fig. 2.

Fig. 4 is a top plan view of an assemblage illustrated in Fig. 3.

Fig. 5 is a top plan view, partly in section, including one of the cutters for performing the first shaping operation, gages for co-operating therewith and broken lines representing a spring-heeled shoe in working position.

Fig. 6 represents the shoe in working position for the final trimming by the assemblage illustrated in Figs. 3 and 4.

Fig. 7 is a perspective view of the heel-end of a shoe that has undergone the first stage of shaping according to Fig. 5.

Fig. 8 represents the same shoe shown in Fig. 7 after it has undergone the final trimming as shown by Fig. 6.

Fig. 9 is a sole plan illustrating the result of using the trimmed periphery of the heel to locate the heel nails in a line parallel to the rand-crease.

Fig. 10 is a longitudinal sectional view of a turn shoe in working position relatively to an edge gage and a nail-driving device of a heel-seat-nailing machine. Figs. 9 and 10 represent different views of the same shoe, although the nail-locating result shown in Fig. 9 can also be obtained in a welt shoe or a McKay shoe.

Fig. 11 is a sole plan of the heel-end of a welt shoe.

Fig. 12 is a longitudinal vertical section

through the heel-end of a welt shoe that has been trimmed, nailed and slugged according to this invention.

Fig. 5 includes a conventional showing of a turned shoe similar to that shown in Fig. 10, the counter portion of the shoe being indicated at 14, the sole at 16, and the wedge lift or lifts of the spring heel at 18. According to common practice in making a shoe of this type, the wedge element 18 is not applied until after the sole-leveling operation. Up to this stage the procedure is regular and need not be described. The heel portion of the sole 16 is not attached to the heel-seat at the stage when the leveling operation is performed because it is necessary to lift it as represented by broken lines in Fig. 10, so that the wedge element 18 may be inserted after the leveling operation. Having inserted the wedge element, which preferably is coated with cement on both faces, the turned-up heel portion of the sole is replaced but now lies on the wedge element. One or two nails 20 will now be driven through the sole, the wedge element 18 and the shank piece 22, and their points will be turned back and clenched by the metal plate 24 with which the last 26 is shod. The wedge element and the heel-end of the sole are thus initially fastened to the heel-seat of the shoe.

To insure sufficient stock in the heel-end of the sole 16 to cover entirely the wedge element 18, said heel end is usually made larger than it will be finally (see projecting marginal portion 28 in Figs. 5 and 9) but the wedge element 18 is usually died out more nearly to the final shape and size and is located nearly in register with the heel-seat of the shoe rather than with the sole. Consequently, before the heel-end of the sole is trimmed it ordinarily projects beyond the wedge element as represented in Fig. 5.

The shoe is now ready to undergo the first step of shaping according to the present invention. This step consists in reducing the periphery of the heel to a uniform distance from the rand-crease by using the rand-crease to determine the course of trimming. As illustrated in Fig. 5, the tread surface of the heel is placed against a tread rest 30 and the rand-crease is placed against a rand-crease gage 32. Although the structural details of the illustrated trimming machine are hereinafter more fully described it may be stated here that the members 30 and 32 are supported adjacent to a rotary cutter-head comprising cutting blades one of which is indicated at 34 in Fig. 5 (see also Figs. 1 and 2). The general organization of the trimming machine herein shown is similar to that shown in Letters Patent of the United States 308,056, granted November 18, 1884, on application of J. H. Busell. The rand-crease gage 32 is adjustable to-

ward and from the axis of the cutter-head to determine the depth of trimming and therefore the width of the extension of the heel beyond the rand-crease, while the tread-rest 30 is also adjustable toward and from the axis of the cutter-head to provide for various diameters of the latter and is adjustable about a vertical pivot member 36 to determine the pitch or slant of the trimmed periphery. This pivot member connects the tread-rest with an adjustable slide 38 which carries an adjusting screw 40. The cutting edges 42 of the blades 34 trim the sole 16 and wedge element 18 flush and produce the result shown in Figs. 7, 9 and 10 in which the trimmed periphery of the heel is indicated at 44.

If it is desired to use the trimmed periphery 44 to locate the nails or pegs by which the heel is to be more securely fastened to the heel-seat of the shoe the latter may now be presented to a nailing or pegging machine. Fig. 10 illustrates how this operation may be performed with a heel-seat nailing machine, but it will be understood that a pegging machine may be used at this stage if it is desired to insert pegs instead of nails. A well-known type of nailing machine comprises a nozzle 46, a driver 48 and an edge gage 50, whereas a well-known type of pegging machine comprises corresponding elements that function in substantially the same way as those about to be described. If desired, a nailing machine of the type shown in United States Letters Patent No. 490,624 granted January 24, 1893, upon application of Louis Goddu, a part of which is shown in Fig. 10, may be used, while the pegging machine (not shown) may be of the type shown in United States Letters Patent No. 581,066, granted April 20, 1897, upon application of Davey and Ladd.

In the use of a nailing machine such as that referred to, the last 26 is placed upon a horn spindle 52 with which such fastener-inserting machines are provided, and the trimmed periphery 44 of the rand-crease extension or wedge element forming the base of the heel is placed against the edge gage 50 and held in contact therewith while the shoe and last are turned about the jack post. The driver 48 is reciprocated by suitable power-driven mechanism to drive heel-seat nails 54 successively from the nozzle 46 and into the heel, and since these nails are located at a uniform distance from the periphery 44 of the base of the heel which has previously been trimmed to a uniform distance from the rand-crease it follows that they will be located at a uniform distance from the rand-crease.

The shoe is now ready for the final trimming of the heel which includes trimming the rand and smoothing the periphery 44.

Fig. 6 shows how this step may be performed by a rotary toothed cutter 56 that takes a fine cut coextensive with the thickness of the heel and has a randing lip 58 which bevels the rand, as indicated at 70 in Fig. 8. The assemblage for this purpose also includes a rand-crease gage 60 and a tread-rest 62. The gage is adjustable transversely of the axis of the cutter to regulate the closeness of trimming. The tread-rest is supported by an adjustable slide 64 to which it is connected by a pivot member 66.

When the coarse cutter comprising the blades 34 is used to perform the first trimming operation, it produces a peripheral surface 44 (Figs. 7, 9 and 10) the contour of which conforms to the counter portion 14 of the shoe, the marginal extension of the heel beyond the rand-crease being thus reduced to uniform width at all points but not beveled or randed. The course of this initial peripheral trimming is guided by the rand-crease and the gage 32. As a result thereof the periphery is trimmed so nearly to its final shape that what little stock remains to be trimmed therefrom is so slight and so evenly distributed as to be no detriment to evenness in the subsequent randing. Since the finishing cutter 56 trims the entire thickness of the periphery 44 in addition to beveling the rand as indicated at 70 (Fig. 8), it forms no "joint" or ridge in the periphery but produces a peripheral surface that needs no scouring. Whatever additional stock is trimmed from the periphery by the finishing cutter 56 is hardly more than enough to smooth the surface formed by the cutters 34. Here also, the rand-crease may be used to insure a uniform width of extension without too much dependence upon the skill of the operative, and for this purpose the rand-crease gage 60 is provided. The result of the final trimming as performed by the assemblage shown in Fig. 6 is represented in Fig. 8 in which the finally trimmed periphery is indicated at 68 and the bevel imparted to the rand by the randing lip 58 is indicated at 70.

So far as I am aware, it is new to trim a heel and bevel the rand as hereinbefore explained, that is, by first trimming the entire periphery of the heel parallel to the rand-crease without beveling the rand, and thereafter simultaneously beveling the rand and trimming the entire periphery to final shape. In addition, the invention provides for rapid production by procedure according to which a relatively coarse and therefore rapid cut is used for the first trimming or peripheral shaping, and a fine cut used for the randing and for finishing the entire peripheral surface produced by the first trimming. The cutters 34 are adapted to execute a coarse cut and to operate much more rapidly than the toothed cutters here-

tofore ordinarily used for trimming spring heels, but the finishing cutter 56 is adapted to make a fine cut and to leave the periphery in suitable condition for edge-setting. Since, according to the method hereinbefore described, the finishing cutter 56 is used merely to trim the rand and smooth the previously trimmed periphery, its duty is comparatively light and it is adapted to perform its operation rapidly and does not require sharpening so often as it has heretofore been necessary to sharpen toothed cutters for this kind of work when all the trimming has been performed by one cutter and in a single operation.

Figs. 11 and 12 exemplify the present invention as utilized in the manufacture of a welt shoe having a spring heel. The shoe shown in Fig. 12 comprises an insole 72, and the wedge element 18 is attached before the outsole 78 is laid. According to the most approved practice in making a welt shoe with a spring heel the procedure up to and including the inseam-trimming operation is no different from that in any other welt shoe. After the inseam has been trimmed the wedge element 18 may be placed in position and initially fastened with one or two nails 74 with or without cement to assist the nails in holding it against displacement. The shoe may now be presented to a heel-seat-nailing machine such as that above mentioned comprising a nozzle and driver indicated at 46 and 48 in Fig. 10 and comprising either an edge gage such as that indicated at 50 or, if preferred, a rand-crease or counter gage to locate the heel-seat nails 76 inside the line of the rand-crease and at the desired distance therefrom. The shoe-bottom-filling and cementing operations may now be performed to prepare the shoe for the outsole 78. A block sole 78 is ordinarily used for a welt shoe, and after being laid it is rough-rounded, stitched and leveled. If desired, the corners 80 of the sole may be cut off to facilitate the trimming operation now about to follow but this is not necessary.

The original outline of the heel end of the outsole is represented in Fig. 11 by a dot-and-dash line, and the original periphery of the wedge element 18 is indicated by a broken line 82. As a result of trimming the heel with the apparatus shown in Fig. 5, the outsole and wedge element are trimmed to the line indicated at 84 which line is a uniform distance at all points from the rand-crease. The result of thus reducing the heel is illustrated also in Fig. 12.

If it is desired to slug the heel, the shoe will be presented to a slugging machine such, for example, as that shown in United States Letters Patent No. 786,190, granted March 28, 1905, on application of L. A. Casgrain, by the use of which the slugs 86 are automatically inserted and spaced one from

another and are located at a uniform distance from the trimmed periphery by an edge gage arranged to function in the same way as the edge gage 50 shown in Fig. 10. Fig. 11 5 includes a broken line representing the line in which the heel-seat nails 76 will be located when inserted as hereinbefore explained, and includes another broken line representing the line in which the slugs 86 may be located. Inasmuch as the periphery 84 would, according to this invention, be trimmed to a uniform distance from the rand-crease before it is used to locate the slugs 86, as above described, the slugs will necessarily 10 be located at a uniform distance from, or in register with, the rand-crease, and the slugs will serve to fasten the heel-end of the sole to the wedge element which has previously been anchored to the bottom of the 15 shoe by the nails 74 and 76. The shoe may now be presented to the finishing cutter 56 (Fig. 6) to trim the rand and to smooth the periphery.

Referring particularly to the trimming machine shown in Figs. 1 to 6, inclusive, by which the trimming operations hereinbefore explained may be performed, the construction comprises a frame 88 having bearings for two horizontal belt-driven shafts 90 and 92. The shaft 90 carries the cutter-head comprising the cutters 34 by which the first step of trimming is performed, while the shaft 92 carries the toothed cutter 56 by which the randing and final trimming are performed. 20 The rand-crease gage 32 is supported by links 94 adapted to swing so that the gage 32 may move toward and from the tread rest 30 according to the thickness of the heel while the tread is maintained in one plane by the 25 tread-rest 30. A spring 96 (Fig. 2) acts on one of the links 94 to urge the gage 32 normally toward the tread-rest. A heel-rest 98 is provided to support the heel against the cutting stress of the cutters 34 and is 30 preferably mounted so that it may be moved up and down by a treadle 100 during the progress of trimming. For this purpose the rest 98 is attached to a vertically movable slide 102 arranged in a guide 104. A link 35 45 connects the slide 102 and the treadle 100. The treadle is connected to a floor plate 108 by a pivot member 110, the latter being located between the ends of the treadle so that the operative, by depressing the heel-end of the treadle, may raise the heel-rest 98 and by pressing the toe-end may lower the heel-rest. The movement required of the heel-rest 98 is slight and may be utilized 50 merely to counteract the variant curvature 55 of the heel so that the point of trimming will remain approximately at a constant level.

Referring to Fig. 4, the tread-rest 62 associated with the finishing cutter 56 is carried by an adjustable plunger 64. This plunger 55 is arranged to slide in a bracket 112 and is

normally urged to the left by a compression spring 114. The plunger 64 has a screw-threaded shank 116 projecting from the right-hand end of the bracket to carry a thumb nut 118 by which its movement to 70 the left may be regulated. The screw 66 by which the tread-rest is pivotally connected to the slide provides for holding the tread-rest frictionally at any desired angle and at the same time permits the tread-rest 75 to swing to various angles according to the desired flare to be imparted to the profile of the heel.

The rand-crease gage 60 is formed with a shank 120 which is arranged to slide in a groove formed in a bracket 122 for purposes of adjustment. A rotary adjusting member 124 having a pinion (not shown) is carried by the bracket to shift the gage transversely of the axis of the cutter according 80 to the diameter of the latter, the shank 120 having rack teeth engaging the pinion. A bolt 126 provides for clamping the shank 120 to the bracket 122 to maintain the gage 85 against accidental displacement. This gage, 90 being stationary, maintains the rand-crease in constant relation to the randing lip 58 while the tread-rest 62 may slide to and fro according to variations in the thickness of the heel. A heel-rest 128 is provided to 95 support the heel against the cutting stress of the cutter 56 and is supported by a pivot member 130 screwed into the bracket 122. A clamping screw 132 is provided to secure the heel-rest 128 in various positions of adjustment.

Having thus described my invention, what I claim as new and desire to secure by Letters Patent of the United States is:

1. That improvement in methods of trimming and randing the heels of shoes which consists in initially trimming the entire peripheral surface of the back and sides of a heel approximately to final shape without randing the heel, using the rand-crease to 105 guide such trimming, and thereafter simultaneously randing the heel and trimming the entire initially trimmed peripheral surface to final shape and using the rand-crease to 110 guide such simultaneous randing and trimming.

2. That improvement in methods of trimming and randing the heels of shoes which consists in initially trimming, with a relatively coarse cut, the entire peripheral surface of the back and sides of a heel approximately to final shape without randing the heel, using the rand-crease to guide such trimming, and thereafter simultaneously randing the heel and trimming the entire 120 initially trimmed peripheral surface to final shape with a relatively fine cut and using the rand-crease to guide such simultaneous randing and trimming.

3. That improvement in methods of trim- 130

ming and randing the heels of spring-heeled shoes which consists in initially trimming the periphery of the sole and of the interposed wedge element in one operation approximately to final shape without randing said wedge element, using the rand-crease to guide such trimming, and thereafter simultaneously randing said wedge element and trimming the periphery thereof and 10 that of the sole to final shape and using said rand-crease to guide such simultaneous randing and trimming.

4. That improvement in methods of trimming and randing the heels of spring-heeled shoes which consists in initially trimming, with a relatively coarse cut, the periphery of the sole and of the interposed wedge element in one operation approximately to final shape without randing said wedge element, using 15 the rand-crease to guide such trimming, and thereafter, with a relatively fine cut, simultaneously randing said wedge element and trimming the periphery thereof and that of the sole to final shape and using said rand-crease to guide such simultaneous randing and trimming.

5. That improvement in methods of trimming and randing the heels of shoes which consists in initially trimming the entire peripheral surface of the back and sides of a heel parallel to the rand-crease without beveling the rand, simultaneously using the rand-crease to control the course of such trimming, and thereafter simultaneously 30 beveling the rand and trimming the entire peripheral surface of the heel to final shape.

6. That improvement in methods of trimming and randing the heels of shoes which consists in initially trimming the entire peripheral surface of the back and sides of a heel parallel to the rand-crease without beveling the rand, using the rand-crease to control the course of such trimming, and thereafter simultaneously beveling the rand and trimming the entire peripheral surface parallel to the rand-crease and using the rand-crease to control the beveling and the final trimming.

7. That improvement in methods of trimming and randing the heels of shoes which consists in initially trimming with a coarse cut the entire peripheral surface of the back and sides of a heel parallel to the rand-crease without beveling the rand, using the rand-crease to control the course of such trimming, and thereafter simultaneously beveling the rand and trimming the entire peripheral surface with a fine cut.

8. That improvement in methods of trimming and randing the heels of shoes which consists in initially trimming with a coarse cut the entire peripheral surface of the back and sides of a heel parallel to the rand-crease without beveling the rand, using the rand-crease to control the course of such trim-

ming, and thereafter simultaneously beveling the rand and trimming the entire peripheral surface with a fine cut and using the rand-crease to guide the beveling and final trimming.

9. That improvement in methods of shaping and randing a spring heel which consists in trimming the periphery of such a heel on the shoe progressively to a uniform distance from the rand-crease while maintaining the tread surface in one plane, and thereafter trimming the rand and said periphery while maintaining the rand-crease in one plane.

10. That improvement in methods of making spring-heeled shoes which consists in preliminarily attaching a wedge element and the heel portion of a sole to the heel-seat of a shoe to provide a spring heel, trimming the periphery of said wedge element substantially parallel to the rand-crease, and thereafter inserting a series of fasteners into the heel and locating them by using the trimmed periphery of said wedge element as a gaging surface.

11. That improvement in methods of making spring-heeled shoes which consists in preliminarily attaching a wedge element and the heel portion of a sole to the heel-seat of a shoe to provide a spring heel, trimming the periphery of the heel parallel to the rand-crease, and thereafter inserting a series of fasteners through the heel and into the heel-seat of the shoe and locating said fasteners at a uniform distance from the rand-crease by using the trimmed periphery of said wedge element as a gaging surface.

12. That improvement in methods of making spring-heeled shoes, which consists in trimming the periphery of the heel of such a shoe to produce a uniform width of extension from the rand-crease by using the latter to control the course of trimming, inserting a series of fasteners in the heel at a uniform distance from the trimmed periphery by using the latter to control the locating of the fasteners, and thereafter trimming the rand and the periphery to final shape at the same time.

13. That improvement in methods of making shoes, which consists in trimming the periphery of the heel of a shoe and controlling the course thereof by the rand-crease to insure a uniform width of extension from the rand-crease, and thereafter inserting a series of fasteners into the heel and heel-seat in uniform relation to the rand-crease by using the trimmed periphery of the rand-crease extension to locate them.

14. That improvement in methods of making spring-heeled shoes, which consists in trimming the periphery of the heel of such a shoe and controlling the course thereof by the rand-crease to insure a uniform width of extension from the rand-crease, inserting

a series of fasteners into the heel at a uniform distance from the trimmed periphery, and thereafter simultaneously randing the heel and smoothing the previously trimmed 5 periphery.

15. That improvement in methods of making shoes, which consists in attaching a heel to the heel-seat of a shoe, trimming the periphery of the heel while controlling the 10 course of trimming by the rand-crease, inserting a series of fasteners to fasten the heel more securely to the heel-seat and locating such fasteners by the previously trimmed periphery, and thereafter randing 15 the heel and smoothing the previously trimmed periphery.

16. That improvement in methods of making shoes, which consists in securing a heel to the heel-seat of a shoe, trimming the pe-

riphery of the heel to a uniform distance 20 from the rand-crease by using the latter to guide the trimming, and thereafter inserting a series of fasteners into the heel at a uniform distance from the rand-crease by using the trimmed periphery of the rand- 25 crease extension to locate such fasteners.

17. That improvement in methods of making shoes which consists in trimming the periphery of the heel of a shoe parallel to the rand-crease and using the latter to guide 30 such trimming, and thereafter inserting a series of fasteners into the heel in a line parallel to the rand-crease by using the trimmed periphery to locate such fasteners.

In testimony whereof I have signed my 35 name to this specification.

THOMAS LUND.
